RAILWAY DRAFT RIGGING

John F. O'Connor, Chicago, Ill., assignor to W. H. Miner, Inc., Chicago, Ill., a corporation of Delaware

Application January 28, 1929. Serial No. 335,478

3 Claims. (Cl. 213—7)

This invention relates to improvements in railway draft riggings.

One object of the invention is to provide a railway draft rigging including the usual coupler means having shock absorbing mechanism cooperating therewith, adapted to be compressed in both buff and draft, and outer follower means cooperating with the shock absorbing mechanism, the coupler having greater travel in buff than in draft, wherein a sleeve is provided for supporting the coupler shank to maintain the horizontal condition of the coupler, the sleeve being formed integral with the outer main follower, whereby maximum extension of the coupler head beyond the outer end of the sleeve is limited to the travel of the same in draft.

Another object of the invention is to provide a railway draft rigging including coupler means and cooperating shock absorbing mechanisms and an inner or rear stop casting for the shock absorbing mechanism, wherein the stop casting has a integral extended portion forming the outer stop means for the shock absorbing mechanism.

Other and further objects of the invention will more clearly appear from the description and claims hereinafter following.

In the drawing forming a part of this specification, Figure 1 is a longitudinal vertical sectional view through a portion of the underframe structure of a car, illustrating my improvements in connection therewith. Figure 2 is a horizontal longitudinal sectional view, corresponding substantially to the line 2—2 of Figure 1. And Figure 3 is a vertical transverse sectional view, corresponding substantially to the line 3—3 of Figure 1.

In said drawing, 10—10 indicate longitudinally extending spaced center sills of the railway car underframe, the sills being of channel shape cross section and extending from end to end of the car. The end sill of the car, which is of substantially channel shape, is designated by 11 and has an opening 12 therein which accommodates the shank of a coupler 13. The coupler 13 is of the usual type and of standard size, a portion only of the head thereof being illustrated in the drawing. The bottom wall of the opening 12 is defined by a carry iron 14 secured to the bottom flange of the end sill and a wear plate 15 is supported on the carry iron. The usual body bolster of the car is designated by 16 and the center sills 10 are secured to the same.

In carrying out my invention, I provide cheek plates 17—17 which are secured to the outer sides of the sills 10 and have reinforced coupler key

receiving slots or openings 18. At the forward ends, the cheek plates have laterally extended portions or flanges 19 which are secured to the vertical web of the end sill 11. A back stop casting 20 is disposed between the sills at the body bolster 16, the same forming also a filler member and having the usual center pin receiving opening 21. The casting 20 is reinforced by intersecting longitudinal and transverse webs and also has forwardly extending strap-like top and bottom members 22—22 comprising spaced side arms and connecting transverse horizontal end sections 23 at the forward extremities thereof. The transverse sections 23 form the front or outer stop means of the railway draft rigging and the front face of the filler portion of the casting 20 forms the rear or inner stop member of the same.

A sleeve member 24 houses the coupler shank and has the outer main follower of the draft rigging formed as a part thereof. The sleeve 24 is of substantially rectangular transverse cross section and has spaced top and bottom walls 25 and 26, spaced side walls 27—27 and a transverse rear end wall 28. The transverse end wall 28 is of greater thickness than the remaining walls of the sleeve and functions as the outer follower of the draft rigging, cooperating with the inner sides of the transverse sections 23 of the strap members 22. As most clearly illustrated in Figure 1, the bottom wall 26 is downwardly offset at the rear end thereof, so as to accommodate the lower transverse section 23. The top wall 25 of the sleeve is cut away at the rear end, as indicated at 29, to accommodate the upper transverse section 23 and permit longitudinal movement of the sleeve inwardly of the car. The side walls 27 of the sleeve terminate short of the rear end thereof and are slotted at their inner ends, as indicated at 30—30, to accommodate the coupler key. As shown in Figure 2, the side walls are flared outwardly and spaced from the side edges of the coupler shank to permit a certain amount of lateral pivotal movement of the coupler with respect to the remainder of the draft rigging. The coupler has a yoke member 31 connected thereto, the yoke member having spaced side arms and a transverse inner end section, the side arms being provided with aligned slots 32—32 to receive the coupler key. The coupler shank 105 is connected to the yoke by means of the usual coupler key 33 which extends through an opening in the coupler shank, the slots 32 of the yoke and the guide slots 18 of the cheek plates of the center sills.

100

105

110

The inner end of the coupler shank bears on the front face of the follower member 28 and is disposed between the sections 23-23 of the top and bottom straps 22, thereby preventing vertical displacement of the coupler shank from its normal horizontal position. At the forward end, the bottom wall 26 of the sleeve has an upturned vertical flange 44 which engages the bottom face of the coupler shank so as to support the front end thereof closely adjacent the coupler head and maintain the same in the horizontal position and in proper alignment with the shock absorbing mechanism of the draft rigging. The top wall 25 of the sleeve also has a vertical flange 10 at the forward end thereof, which is formed interiorly of the sleeve and reinforces the same at the end portion thereof. The bottom edge of this flange, as clearly shown in Figure 1, is spaced an appreciable distance from the top face of the 20 coupler shank.

A friction shock absorbing mechanism, comprising a friction shell 34, cooperating friction shoes 35 and a wedge member 36, all of well known form, is interposed between the front 25 face of the filler casting 20 and the inner end of the yoke 31. As will be understood, the usual spring resistance means is disposed within the shell 34 and cooperates with the friction means comprising the shoes and wedge member.

30 A spring shock absorbing mechanism is disposed within the yoke 31, the same including a rear follower member 37 in the form of a substantially rectangular block having longitudinally extending top and bottom spring receiving pockets 38-38 which open through the front end of the block and are closed at the rear ends by an end wall 39.

The end wall 39 is transversely recessed, as indicated at 40, to receive the transverse section 40 of the yoke 31, whereby the outer face of the transverse section of the yoke will be flush with the rear end face of the block 37. Top and bottom spring members 41-41 are disposed within the pockets 38 and have their front ends bearing on 45 the inner side of the outer follower member 28. Each of the spring members 41 preferably includes inner and outer coils. The front end of the sleeve is spaced from the follower so as to allow a certain amount of compression of 50 the springs 41 when the follower and block are moved relatively to each other and limit such compression by engagement of the follower with the block. In the normal position of the parts, the coupler key 33 has the front edge thereof spaced a sufficient distance from the outer end 55 walls of the slots 18 of the draft sills to permit of the maximum relative movement between the block 37 and the follower 28 in draft. The inner edge of the coupler key is spaced from the inner end walls of the slots 32 of the yoke a distance substantially equal to the spacing between the outer follower 28 and the block 37, so that the key will engage the end walls of the slots 32 at substantially the same time that the follower 60 engages the block, whereby the yoke and block 37 will move in unison during the remainder of the inward stroke of the coupler, the force being then transmitted from the yoke to the wedge 36 of the friction shock absorbing mechanism. The compression of the friction shock absorbing mechanism is limited by engagement of the transverse section of the yoke with the front end of the friction shell, and also by the follower 70 block 37 engaging the shell.

75 As shown in the drawing, the follower block 37

and the friction shell 34 are supported in operative position by carrier plates. The normal spacing of the inner edge of the coupler key 33 and the inner end walls of the slots 18 of the draft sills preferably exceeds the combined spacing 80 between the inner end of the yoke and the friction shell 34, thereby permitting free inward travel of the key in buff during the entire compression stroke of the mechanism as both the spring and friction gears are being compressed to the full limit of their movement.

In the operation of my improved railway draft rigging, assuming a buffing action being applied to the coupler, the coupler will be forced inwardly 90 carrying the follower member 28 therewith and compressing the springs 41 against the end wall of the block 37 and the transverse end section of the yoke 31, the pressure being transmitted from the yoke directly to the wedge 36 of the friction 95 shock absorbing mechanism, movement of the latter inwardly being resisted by the stop or filler casting 20. During the inward movement of the coupler, both the spring and friction shock absorbing mechanisms will be compressed, the compression of the spring shock absorbing mechanism being limited by engagement of the follower member 28 with the front end of the block 37. After relative movement of these parts has been thus limited, the block and follower 28 together 100 form a solid column and transmit the actuating force directly to the end of the yoke and wedge 36 during the remainder of the compression stroke. The compression of the friction shock absorbing mechanism is limited by engagement 105 of the transverse section of the yoke and follower block 37 with the front end of the friction shell 34, as hereinbefore pointed out.

As will be evident, the inward travel of the coupler during a buffing action, is thus equal to the 110 combined compression strokes of the friction and spring shock absorbing mechanisms. When the actuating force is reduced, the expansive action of the spring of the friction shock absorbing means will force the friction shoes and wedge 115 block 36 outwardly, carrying the yoke 31 and the block 37 therewith. At the same time, the expansion of the springs 41 of the spring shock absorbing mechanism will force the follower member 28 outwardly until the same is arrested 120 by engagement with the transverse sections 23 of the strap members 22. As the follower 28 forms a part of the sleeve 24, the coupler head will remain spaced the same distance from the outer end of the sleeve during the entire buffing stroke of 125 the mechanism and during the releasing action following the buffing action. As shown in Figures 1 and 2, the coupler head is normally spaced only a slight distance from the front end of the sleeve, so that the point of support of the coupler 130 shank will be closely adjacent the head.

Assuming a draft or pulling action as being applied to the coupler, the same will be moved outwardly, carrying the yoke 31 therewith and compressing the springs 41 between the inner end 140 of the yoke and the follower member 28, the latter being held in fixed position by engagement with the transverse stop sections 23 of the straps 22. Outward movement of the coupler in draft will be limited by engagement of the block 37 with 145 the follower 28, thus limiting the extension of the coupler to the amount of relative travel of the block 37 and the follower 28 during full compression of the spring shock absorbing mechanism,

This travel preferably does not exceed the normal compression of draft gears now employed in standard railway practice, whereby the coupler head at no time will be spaced such a distance 5 from the outer end of the sleeve as to endanger the trainman, that is, the travel of the coupler head, with respect to the sleeve, is not great enough to permit the trainman's foot being caught between the parts and injured when the 10 coupler head approaches the end of the sleeve. Upon the actuating force being reduced, the expansive action of the springs 41 will restore the yoke, sleeve and coupler to the normal full release position shown in the drawing.

15 While I have herein shown and described what I consider the preferred manner of carrying out my invention, the same is merely illustrative and I contemplate all changes and modifications which come within the scope of the claims appended hereto.

I claim:

1. In a draft rigging for railway cars, the combination with spaced center sills; of shock absorbing means between said sills; a coupler having a shank; a yoke connecting the coupler to said shock absorbing means; a rear stop casting having a forwardly extending loop member, said loop member including spaced side arms and a transverse front end section forming a front stop member; a carry iron at the end of the car fixed to said sills; and a supporting slide movable on the carry iron, the outer end portion of said slide normally engaging the coupler shank in supporting relation outwardly of the carry iron member, said slide overlapping the carry iron in all operative positions, said slide having an upstanding front follower plate member at the rear end thereof formed integral therewith, said follower plate having free top and free vertical side edges, said plate being interposed between the transverse front section of said loop member and the shock absorbing means.

2. In a draft rigging for railway cars, the combination with spaced center sills; of shock absorbing means between said sills; a coupler having a shank; a yoke connecting the coupler to said shock absorbing means; a rear stop cast-

ing having a forwardly extending loop member, said loop member including spaced side arms and a transverse front end section forming a front stop member; a carry iron at the end of the car fixed to said sills; and an outer follower plate cooperating with the shock absorbing means, said follower having an integral sleeve portion guided on the carry iron and receiving the coupler shank, the outer end section of said sleeve normally engaging the coupler shank in supporting relation outwardly of the carry iron, said sleeve overlapping the carry iron in all operative positions of the sleeve, said sleeve immediately adjacent said follower plate being open at the top and sides, and said follower plate being interposed between the shock absorbing means and the end section of said loop member.

3. In a draft rigging for railway cars, the combination with spaced center sills; of a carry iron at the end of the car fixed to said sills; shock absorbing means between said sills; a coupler having a shank; a yoke connecting the coupler to said shock absorbing means, a combined rear stop and filler casting between said sills, said casting having top and bottom forwardly extending loop shaped members formed integral therewith, each loop shaped member including a pair of spaced side arms and a transverse front section, said front sections forming front stop means; and a combined front follower and support comprising a plate-like member and a sleeve, said sleeve having top, bottom and side walls, said bottom wall extending rearwardly beyond said top and side walls, said plate member being at the rear end of said bottom wall and formed integral with said bottom wall, said plate being spaced from said top and side walls of the sleeve and interposed between the shock absorbing means and the front sections of said loop shaped members, said sleeve receiving the coupler shank and being guided on the carry iron, the forward end section of said sleeve normally engaging the coupler shank in supporting relation outwardly of the carry iron, said sleeve overlapping the carry iron in all operative positions of the sleeve.
